(57) **CLAIM**

The ornamental design for a drain outlet, as shown and described.

DESCRIPTION

FIG. 1 is a top perspective view of a drain outlet according to my new design;

FIG. 2 is a bottom perspective view thereof;

FIG. 3 is a front view thereof;

FIG. 4 is a back view thereof;

FIG. 5 is a left side view thereof;

FIG. 6 is a right side view thereof;

FIG. 7 is a top view thereof;

FIG. 8 is a bottom view thereof; and,

FIG. 9 is a center sectional view taken from line 9-9 of FIG. 7.

The dashed lines shown in the drawings illustrate environmental structure and form no part of the claimed design.
